[57] CLAIM

The ornamental design for a wall supported hose reel, as shown and described.

DESCRIPTION

FIG. 1 is a perspective view of a wall supported hose reel showing our new design looking down from the right side of the hose reel;

FIG. 2 is a front elevational view thereof;

FIG. 3 is a top plan view thereof, the bottom plan view being identical thereto; and,

FIG. 4 is a left side elevational view thereof, the right side elevational view being a mirror image thereof.

FIG. 1FIG. 2FIG. 4
